UNITED STATES PATENT OFFICE.

IRL R. HICKS, OF CENTRALIA, MISSOURI.

PROTECTING-SHELL FOR SPARK-PLUGS.

1,388,709.

Specification of Letters Patent. Patented Aug. 23, 1921.

Application filed December 5, 1918. Serial No. 265,422.

To all whom it may concern:

Be it known that I, IRL R. HICKS, a citizen of the United States, residing at Centralia, in the county of Boone and State of Missouri, have invented certain new and useful Improvements in a Protecting-Shell for Spark-Plugs, of which the following is a specification.

This invention comprehends generally improvements in that class of inventions known 10 as spark plugs and more particularly relates to a protecting shell for spark plugs.

It is a well known fact that when an engine is hot and the outside portion of the 15 porcelain core of the spark plugs in the engine is exposed to a sudden cold draft of air, rain or snow, that the porcelain core will crack near its point of connection with the spark plug base and be rendered use- 20 less. It is the principal aim and object of this invention therefore to provide a pro- 25 tecting shell formed of insulating material and designed to be arranged about the plug and spaced from the porcelain core thereof 30 to provide an air chamber about the core and thereby shield the core from sudden changes 35 of temperature and in consequence prevent the breakage of the core.

It is a more specific object of this inven- 40 tion to provide a device of the above men- tioned character wherein the body of the shell is of novel construction; and to also provide a reinforcing eyelet about the opening in the top of the shell.

Among the other aims and objects of this 45 invention may be recited the provision of a device of the above mentioned character wherein the number of parts are compara- 50 tively few, the construction simple, the cost of production low and the efficiency high.

Other objects, as well as the nature, char- 55 acteristic features and scope of this inven- tion will be more readily apparent from the following description taken in connection 60 with the accompanying drawings and pointed out in the claims, forming a part of this specification.

In the accompanying drawings, the figure 65 represents a side elevation showing the shell applied to a spark plug, the shell being partly broken away to illustrate the con- 70 struction thereof.

Referring now, more particularly, to the 75 accompanying drawings, there is illustrated a spark plug indicated in its entirety by the

numeral 1 desirably of the usual form al- 80 though it may be stated to consist generally of a main central electrode 2 about which is arranged a porcelain core 3 the lower end of which is mounted in the hexagon shaped 85 attaching base 4 in the usual manner and the upper projecting threaded portion of the central electrode has detachably mounted thereon the terminal clamping nut 5 which acts as a means for releasably holding the 90 improved protecting shell generally designated 6 in the proper position on the spark plug.

In reducing the present and improved 95 construction of shell to practice, the same 70 may be said to consist of a cap-like body 7 formed of insulating material the main portion of which is desirably of a hexagon configura- 75 tion in cross section so as to fit snugly about the upper portions of the sides of the correspondingly spaced base 4 of the spark 80 plug while the upper portion of the body of the shell is restricted to provide a top 8 which is preferably rounded and formed with a central opening 9 for disposition 85 about the upper projecting portion of the electrode, before the application of the clamping nut 5, and on the upper end of the porcelain core 3. When in this position, 90 an air space or chamber 10 is provided be- 85 tween the outer surface of the core 3 and the inner surface of the shell to protect the porcelain core from sudden changes of tem- 95 perature and thereby prevent breaking of the core.

It is preferred that a metallic eyelet 11 be 100 fitted in the opening 9 for reinforcing and protecting the top 8 about the opening there- 105 in, and, subsequent to the application of the shell the clamping nut 5 is engaged with the threaded projecting portion of the central electrode 2 for clamping the shell in the proper position, the clamping action being on the eyelet 11 instead of on the top of the projecting shell, thereby increasing the longevity of the device, as is apparent. It is also preferred that the lower outer edge of the body of the shell be rounded as at 12 thereby relieving the projecting corners as is apparent.

It is evident that the shell may be ap- 105 plied to substantially any standard type of spark plug without any modification what- ever in the original construction thereof, and when so applied will effectively protect

the insulator of the plug against the danger of rapid cooling and provide a guard preventing the insulator from being struck and broken.

5 Still further embodiments of the invention than those herein especially defined may be resorted to as conditions or preference may dictate, as may be in keeping with the hereto appended claims.

10 Having thus fully described the invention, what is claimed as new and desired to be secured by Letters Patent, is:

1. A protecting shell for spark plugs comprising a cylindrical body having a con-
15 vexed closed end and an opposite open end, said closed end having a central aperture therein adapted to receive the central electrode of said plug when the body is telescoped thereover, said body being freely re-
20 movable therefrom, and being of a diameter considerably greater than the upper portion of the plug to space the inner surface of said body from the shell of the plug and having its open end shaped correspondingly

to the shell of said plug to snugly embrace 25 the same.

2. A protecting shell for spark plugs constructed of insulating material and comprising a cylindrical body having a convexed closed and an opposite end, said closed end 30 having a central aperture therein for receiving a reinforcing eyelet to space the top of the body from the shell of the spark plug, and adapted to receive the central electrode of said plug when the body is telescoped 35 thereover, said eyelet also constituting a bearing surface for the terminal clamping nut of said plug, said body being of a diameter considerably greater than the upper portion of the plug to space the inner surface 40 thereof from the body of the shell and having its open end shaped correspondingly to the circumference of the shell and snugly embracing the same to prevent the admission of dirt or oil. 45

In testimony whereof I affix my signature hereto.

IRL R. HICKS.
